UNITED STATES PATENT OFFICE

2,625,694

SIDE EXTENSION FOR CRIBS AND THE LIKE

Jacques L. Moss, Detroit, Mich.

Application January 6, 1951, Serial No. 294,725

5 Claims. (Cl. 5—331)

1

The present invention pertains to a novel extension for the sliding gate of a baby crib, play pen or the like.

The extensions of this character that are already known in the art are secured rigidly to the upper edge of the sliding gate. When the gate is lowered, such extensions remain upright on the gate and constitute objectionable obstruction to ingress to the interior of the enclosure.

The principal object of this invention is to provide an extension that can easily be folded so as to prevent the extension from being a barrier when entrance to the enclosure or crib is desired, especially when the sliding gate is lowered. This is an improvement in children's cribs and crib guard extensions, to provide novel means to enhance safety and convenience in bed making, etc. More particularly, the extension is hinged relatively to the gate and can be swung downward or outward on releasing a latch. In this connection, this extension must be independent of the fixed posts of the structure; and another object of the invention is to provide an extension mounted in this manner.

In the accomplishment of these objects, a pair of clamps are fitted on the upper rail of the sliding gate. To each of the clamps is hinged the lower end of an arm, so that the arms swing upward toward the clamps and downward away from the clamps. The arms carry a bar that lies above the upper rail when the arms are in the raised position. The arms also carry releasable latches for attaching to the straps.

If desired, a single clamp and arm may be employed, and in such a construction the arm would carry the extension bar centrally. However, a preferred and more rigid construction is provided by the use of two clamps and arms so that the bar is supported near each end.

The invention is fully disclosed by way of example in the following description and in the accompanying drawings in which:

Figure 1 is an inner side view of a crib equipped with the invention;

Figure 2 is a section on the line 2—2 of Figure 1;

Figure 3 is a section on the line 3—3 of Figure 2;

Figure 4 is a section on the line 4—4 of Figure 1;

Figure 5 is a longitudinal section of a modified form of latch, and

Figure 6 is a section on the line 6—6 of Figure 5.

Reference to these views will now be made by

2

use of like characters which are employed to designate corresponding parts throughout.

In Figure 1 is shown a portion of a baby crib and sufficient to illustrate a pair of posts 1 between which is mounted a vertically slideable gate 2. It will be understood that the invention is also applicable to analogous structures such as a play pen or the like. Rings 3 extending from the ends of the gate, at the top and bottom, are slideable on guide rods 4 mounted vertically on the posts 1.

Any conventional stop means may be used to retain the gate in the elevated position. For example, forks 5 are slidably mounted on the ends of the upper rail 6 of the gate 2. The stems of the forks are slideable in retaining sleeves 7 on the rail 6. The forked ends rest upon collars 8 fixed on the rods 4. On each fork stem is an expanded coil spring 9 having its ends connected respectively to the corresponding sleeve 7 and the inner end of the stem, to draw the forked end over the adjacent collar 8. The forks are released from the collars by being pulled inward against the tension of the springs.

On the upper rail 6 of the sliding gate 2 is mounted a pair of clamps, each comprising a flat strap 10 engaging the outer surface of the rail and a bent strap 11 engaging the inner surface of the rail. The ends of the strap 11 are thus brought against the ends of the strap 10 and are secured to the strap 10 by any suitable means such as bolt and nut assemblies designated by the numeral 12. Felt linings may be secured to the straps or to the sides of the rail 6 to prevent marring by direct contact of metal to wood.

To the lower end of each strap 10 is attached the lower end of an arm 14 by means of a hinge 15. The arm 14 is considerably longer than the strap 10 for a purpose that will presently appear.

The upper end of each arm is bent to form a socket 16 cooperating with a complementary member 17 fastened to the upper end of the arm by a bolt and nut assembly 18. Two substantially circular sockets are thus formed for the purpose of retaining an extension bar 19 that stands parallel to the rail 6 and a suitable distance above it.

Before assembling the bar 19, a slide 20 is mounted on each arm 14 and is of sufficient size to embrace the adjacent strap 10 shown in Figure 2. A cup 21 is formed to the back of the slide 20. Through the cylinder and back of the slide is mounted a slideable pin 23 having a knob 24 outside the cylinder while the inner end is adapted to enter a hole 25 in the arm 14 at a

point adjacent to the upper end of the corresponding strap 10. Thus, the slide is locked to the arm 14 while embracing the strap 10. The pin is held in the hole 25 by a surrounding coil spring 26 mounted in the cylinder 21 and bearing on a collar or pin 27 secured to the locking pin 23.

The slide 20 is also formed with a pair of inwardly stamped tongues that extend over the edges of the arm 14 and between the arm and the adjacent strap 10 when the slide is locked. The tongues 28 retain the slide in a restrained sliding engagement with the arm 14 when the slide is moved off the upper end of the strap 10 and the pin 23 bears on the surface of the arm. A rubber bumper 29 is inserted between the arm 14 and the strap 10 below the slide in the locked position of the latter.

In order to obtain access to the infant in the crib or play pen, the extension is swung downward either before or after dropping the gate 2 as desired, in the usual manner. In order to swing the extension downward, the pins 23 are first pulled out of the holes 25 in the arms 14. The slides 20 are then moved upward to clear the upper ends of the straps 10, and the bar 19 is then free to swing downward with the arms on the hinges 15. When the gate 2 is to be raised, the extension is elevated and latched in the reverse manner.

Figure 5 shows a modified form of latch. Each of the arms 14, and the adjacent strap 10 has a vertical slot 31 opposite the opening 30. A housing or fitting 32 is mounted on the outer surface of the arm 14 over the opening 30, and a latch rod 33 is rotatably mounted in the housing and opening. Outward of the housing the rod carries a handle or knob 34, while the free or inner end of the rod is formed as a hook 35 adapted to pass through the slot 31 while lying lengthwise thereof. A torsion spring 36 within the housing 32 surrounds the rod 33, with one end secured thereto and the other end secured to the housing. The spring is tensioned so that it turns the rod 33 to a position wherein the hook 35 traverses the slot 31 and is thereby latched against the strap 10. When it is desired to swing the arm 14 downward, the knob 34 is merely turned to aline the hook 35 with the opening 31 for passage therethrough.

Although specific embodiments of the invention have been illustrated and described, it will be understood that various alterations in the details of construction may be made without departing from the scope of the invention as indicated by the appended claims.

What I claim is:

1. An extension for the side of a crib, play pen or the like, comprising a strap, means for clamping said strap vertically on the upper edge of such side, said strap and said means having opposed and spaced vertical clamping surfaces between which such side is receivable, a vertical arm having its lower end hinged to said strap, a bar carried by the upper end of said arm and perpendicular to said arm, and means for latching said arm to said strap.

2. An extension for the side of a crib, play pen or the like, comprising a strap, means for clamping said strap vertically on the upper edge of such side, said strap and said means having opposed and spaced vertical clamping surfaces between which such side is receivable, a vertical arm having its lower end hinged to said strap, a bar carried by the upper end of said arm and perpendicular to said arm, said bar lying upward beyond said strap, a slide on said arm and adapted to embrace said strap, and means for latching said slide to said arm at a point opposite said strap.

3. An extension for the side of a crib, play pen or the like, comprising a strap, means for clamping said strap vertically on the upper edge of such side, said strap and said means having opposed and spaced vertical clamping surfaces between which such side is receivable, a vertical arm having its lower end hinged to said strap, a bar carried by the upper end of said arm and perpendicular to said arm, said bar lying upward beyond said strap, a slide on said arm and adapted to embrace said strap, said arm having an aperture at a point opposite said strap, and a spring-pressed pin carried by said slide and adapted to enter said aperture.

4. An extension for the side of a crib, play pen or the like, comprising a pair of spaced straps, means for clamping said straps vertically on the upper edge of such side, said straps and said means having opposed and vertical clamping surfaces between which such side is receivable, a pair of vertical arms having their lower ends hinged respectively to said straps, a bar carried by the upper ends of said arms and perpendicular to said arms, and means for latching said arms to said straps.

5. An extension for the side of a crib, play pen or the like, comprising a strap, means for clamping said strap vertically on the upper edge of such side, said strap and said means having opposed and spaced vertical clamping surfaces between which such side is receivable, a vertical arm having its lower end hinged to said strap, a bar carried perpendicularly by the upper end of said arm and perpendicular to said arm, and a hooked releasable latch passed through said arm and strap.
